AUTOMOBILE SUN VISOR

Daniel A. Berkoff, Sherman Oaks, Calif., assignor to Hollywood Accessories, a division of Orion Industries,
Inc.

Filed May 11, 1970, Ser. No. 22,932

Term of patent 14 years

Int. Cl. D12—14

U.S. Cl. D14—6

FIG.1

FIG.4

FIG. 1 is a perspective view showing an automobile sun visor embodying my new design;

FIG. 2 is a front elevational view of said sun visor;

FIG. 3 is a rear elevational view of said sun visor; and
FIG. 4 is a side elevational view of said sun visor with the side opposite that shown bearing the same appearance.

I claim:

The ornamental design for an automobile sun visor, substantially as shown and described.
